[57] CLAIM

The ornamental design for a side rail for a land vehicle luggage rack, as shown and described.

DESCRIPTION

FIG. 1 is a perspective view of the side rail for a land vehicle luggage rack showing my new design;

FIG. 2 is a side elevational view hereof;

FIG. 3 is a front elevational view hereof;

FIG. 4 is a rear elevational view hereof;

FIG. 5 is a bottom plan view hereof;

FIG. 6 is a top plan view hereof;
FIG. 7 is a perspective view of a side rail for a land vehicle luggage rack showing a second embodiment of my new design; and

FIG. 8 is a side elevational view of FIG. 7.
